UNITED STATES PATENT OFFICE.

JOSEPH B. LAUGHTON, OF WESTFIELD, MASSACHUSETTS.

INK-PAD.

SPECIFICATION forming part of Letters Patent No. 538,837, dated May 7, 1895.

Application filed August 10, 1893. Renewed March 2, 1895. Serial No. 540,344. (No model.)

To all whom it may concern:

Be it known that I, JOSEPH B. LAUGHTON, a citizen of the United States, and a resident of Westfield, in the county of Hampden and 5 State of Massachusetts, have invented new and useful Improvements in Ink-Pads, of which the following is a specification.

My invention consists of a roller inking pad adapted for inking stamps of greater length 10 than the length or breadth of the pad and especially adapted for inking flexible stamps to better advantage than flat pads, and it also consists of a combined roller and flat pad each adapted for its special uses, and also adapted 15 for utilizing the roller pad as an inking roller for distributing the ink on the flat pad and on itself also, and thus providing the flat pad with the best of all known means of distributing the ink, for lack of which a brush or 20 cloth is now used with very inferior effect, all as hereinafter fully described reference being made to the accompanying drawings, in which—

Figure 1 is a bird's-eye view of my improved 25 combined roller and flat pad in the normal conditions with the cover raised. Fig. 2 is a similar view with the roller-pad in the condition for use as an inking-roller for the flat pad and for distributing the ink on itself. Fig. 3 is a transverse section of the combined flat 30 and roller pad on line $x-x$, Fig. 1. Fig. 4 is a transverse section of the combined roller and flat pad on line $y-y$, Fig. 2. Fig. 5 is an end view of the combined pad with part of a stamp, 35 showing the manner of inking a flexible stamp or a stamp too long to be inked by one stroke on the flat pad. Fig. 6 is a side elevation of the roller-pad as it may be provided for use independently of the flat pad for long stamps, 40 and also for flexible stamps, and being about as useful for short stamps as a flat pad. Fig. 7 is an end elevation of the roller-pad with the cover of its case opened, and Fig. 8 is an end elevation of the roller-pad with its cover 45 closed.

For inking long stamps as a , also flexible stamps that it is difficult to ink uniformly on a flat pad as b , I provide a roller pad c , mounted on pivots d , so that the stamp can be rolled 50 lengthwise on the roller as indicated in Fig. 5, and thus be inked uniformly from end to

end, and enabling a much smaller pad to serve for long stamps than will serve in flat shape except by striking the stamp on it two or more times which is objectionable both on account 55 of the extra labor, and the lack of uniformity in the application of the ink to the stamp.

For greatest utility I combine a flat pad b , and a roller pad c in suitable relation in one article whereby with both pads of small size 60 the kit is adapted for stamps of any length and also for rigid or flexible stamps, and I mount the roller pad detachably from the bed piece e , of the pad holder and in a holder f , whereby it may be taken in the hand and be 65 rolled along the surface of the flat pad as represented in Fig. 4, for distributing the ink on both pads, the ink being first applied to either one by a brush or swab, or by dripping on to it. The said holder consists in this case of a 70 box open at the top and having the roller pivoted in its ends with a flange g , at each end to rest on the surface of the bed-piece e having a recess h at the side of the flat pad in which the said holder is placed for its connection in the combined article and for use as a 75 roller pad, but the said holder may be constructed in any other approved way whereby it may occupy its place in the said combined article and whereby it may be conveniently 80 taken up and rolled on the flat pad.

For use of the roller pad independently of the flat pad the box for holding it will preferably have a little broader base as f' Figs. 6, 7 and 8, and a semi-circular cover h will be 85 provided and arranged to swing on the roller pivots d , for covering and uncovering the roller, with a hook and staple i , for fastening the cover when closed.

The bed frame e , for the combined pads is 90 provided with the usual cover j , which is hinged to the bed piece in the usual manner and so as to incase both pads when closed.

The body of the roller pad is to be covered 95 with any suitable material as felt or the like as in flat pads for a container and distributor of the color, paste or ink.

I claim—

1. The combination in an inking pad of the flat pad, the inclosing case therefor having 100 the recess in the bed piece alongside of the flat pad, the ink roller, and the ink roller

holder, said holder and its roller detachably located in the recess of the bed piece, suitable for use as a roller pad, and for being removed and used as an inking roller to the flat pad substantially as described.

2. The combination in an inking pad, of a bed carrying a flat pad, the inking roller, the box holder for said roller constituting a supporting base for it when used as a roller pad, to a handle for said roller when used as an inking roller, and the bed piece of the flat pad

having the recess for said roller and holder substantially as described.

In testimony that I claim the foregoing as my invention I have signed my name, in presence of two witnesses, this 3d day of April, 1893.

JOSEPH B. LAUGHTON.
